DICROTONIC ESTERS

Don E. Floyd, Minneapolis, Minn., assignor to
General Mills, Inc., a corporation of DelawareNo Drawing. Application July 10, 1948,
Serial No. 38,162

7 Claims. (Cl. 260—485)

1

The present invention relates to improvements in the process of converting crotonic esters to esters of alpha-ethylidene-beta-methyl glutaric acid, commonly called dicrotonic esters. This application is a continuation-in-part of my co-pending application, Serial No. 632,597, filed December 3, 1945, now abandoned. Dicrotonic acid and its esters are useful as plasticizers and as intermediates for the preparation of condensation polymers, alkyd resins, interpolymers with other unsaturated compounds, and as intermediates in general organic syntheses. The preparation of dicrotonic acid and its esters by condensation of crotonic esters has been known. For example, Von Pechmann, Ber. 33, 3323 (1900) prepared the dimethyl ester of dicrotonic acid by warming a mixture of ether, methyl crotonate, and an equi-molecular amount of sodium methylate for a period of three to four hours. He claimed a yield of 60-70% of dicrotonic acid dimethyl ester. No data is given as to the purity of the product obtained. Actual repetition of Von Pechmann's work indicates a yield of around 43% based on methyl crotonate fed to the reaction, and about 55% based on methyl crotonate consumed. This method entails definite disadvantages in that it involves the use of equi-molecular amounts of sodium methylate, a catalyst which is expensive to prepare and use. Furthermore, the yields are low, particularly as a result of certain side reactions such as acyloin condensation, acetoacetic ester type self-condensation, reduction by sodium, polymerization, and addition of the alcoholate to the double bond in the crotonic ester. The by-products resulting from these side reactions not only reduce the yield, but actually contaminate the product obtained, thereby necessitating extensive purification.

Another attempt at the production of dicrotonic acid and its esters is reported by Michael, Ber. 33, 3731 (1900), who allowed a mixture of ether, ethyl crotonate, and approximately half the molar amount of metallic sodium to stand at room temperature for three days. He reported a yield of about 25% of dicrotonic acid diethyl ester. This procedure entails essentially the same disadvantages as those reported by Von Pechmann. Moreover, the extended time period required is disadvantageous from a production standpoint, and at the same time permits side reactions to proceed to a greater extent.

It has now been discovered that it is possible to carry out this condensation under conditions which permit it to proceed to substantial completion in a relatively short period of time, while at

the same time utilizing only a relatively small amount of catalyst, effecting high yields of a product, requiring a minimum of purification, and yielding a minimum of side reaction products.

2

It is, therefore, an object of the present invention to provide a process of preparing dicrotonic acid and its esters in high yield with a minimum amount of by-products in a comparatively short period of time without the necessity of extensive purification and with the consumption of relatively small quantities of catalyst.

Other objects will be more fully apparent from the following description of the invention.

The invention consists of carrying out the condensation of crotonic esters at an elevated temperature preferably in the presence of a high boiling solvent and in the presence of a small amount of catalyst, for a comparatively short period of time. Temperatures preferably in excess of 70° C. and up to 200° C. or higher are suitable. Such temperatures may be employed in the absence of a solvent but are preferably employed with a solvent in view of the difficulty of maintaining temperature control in the absence thereof. High boiling, inert solvents such as aromatic and aliphatic hydrocarbons, ethers, and the like may be employed. By operating at elevated temperatures and by using small quantities of catalysts, side reactions have been reduced to a minimum or eliminated completely and a more complete condensation to the dicrotonic ester obtained. The solvents employed can be recovered practically quantitatively by distillation. They are not as subject to loss through volatilization or to fire hazard as is the case with ethyl ether. Moreover, they are readily obtained commercially in an anhydrous condition and free of interfering substances such as alcohols. Not only has the yield in this condensation been improved, but the purity of the reaction product has also been improved. Conversion of the crotonic ester is nearly complete while at the same time competing side reactions are minimized. This eliminates unchanged starting material and certain side reaction products as impurities. Therefore, extensive purification by fractionation or by other means is unnecessary.

The reaction is carried out by mixing the crotonate with a solvent in a flask fitted with a mechanical stirrer and condenser protected by a drying tube. A small amount of catalyst is then added and the mixture stirred and refluxed

for a period of several hours. By this time the reaction is substantially complete as evidenced by the absence of the pronounced odor of the crotonate. The reaction mixture is then cooled and shaken with dilute acid to effect removal of the alkaline catalyst. The removal of the last traces of acid, alkali, or salts may be effected by water-washing and then drying. Following distillation of the solvent, the dicrotonate product may be vacuum distilled. In order to obtain a product of utmost purity the dicrotonate may be subjected to a fractional distillation. As an alternative, the ester may be hydrolyzed to the free dicrotonic acid which may then be obtained in the pure form by crystallization.

A period of three to twelve hours is usually required for the reaction. With very active catalysts, such as powdered sodium hydride, usually three to four hours is sufficient, while with less active catalysts more time is required. The reaction temperature also has a pronounced effect on the reaction and in general a high temperature promotes more rapid reaction. Finely powdered catalysts which are readily dispersed also promote more rapid reaction than those with coarser particle size.

Several variations are permissible in the various factors involved in the reaction. For example, the crotonate employed may be an ester containing an aliphatic, aromatic, aryl-aliphatic, alicyclic, or heterocyclic alcohol residue which may be saturated or unsaturated and may or may not contain substituent groups which do not react with or interfere with the catalyst. In general, as the groups become larger, the reactivity of the ester is less and accordingly the reaction rate is lower. Accordingly, it is preferred to employ lower aliphatic esters such as methyl, ethyl, propyl, butyl, and the like.

The solvents employed should be relatively inert toward the reactants and have a medium to high boiling point. In general, aromatic hydrocarbons, aliphatic hydrocarbons, aryl-aliphatic hydrocarbons, and ethers, both symmetrical and mixed, may be employed. Examples of such solvents are benzene, toluene, xylene, diethyl ether, high boiling petroleum solvents, and the like. The time of reaction will depend upon a number of factors such as the solvent used, temperature of reaction, and the catalyst. Since it is ordinarily desired to secure a quantitative conversion of the crotonic ester, heating should be continued until the pronounced odor of the crotonic ester has disappeared. Another way of detecting substantial completion of the reaction is to watch the temperature, which will gradually rise until the conversion is complete at which point the temperature will remain fairly constant, or the rate of temperature rise will be reduced considerably. Prolonged heating beyond the point of reaction will reduce the yield of the dicrotonic ester while increasing the amount of polymerization products.

Various catalysts are satisfactory for the reaction. They include metallic sodium and potassium, sodium and potassium methoxide, ethoxide, and the like. In general, the alkali metals and their basic derivatives such as alkoxides, amides, hydrides, alkyls, and the like, are most suitable. Certain other metals and their derivatives possess some activity as is well known by those skilled in the art. When metals such as sodium are used as catalysts the principal competing reactions are acyloin condensation, acetoacetic type self-condensation, and reduction by the metal. In

order to eliminate or minimize these reactions it is important to use very small amounts of metallic catalyst. When metal alcoholates are used as the catalyst the principal competing reactions are the production of beta-alkoxybutyric esters by addition to the double bond in the crotonic ester and the acetoacetic ester type self-condensation. In this case the use of a small amount of catalyst eliminates or minimizes these side reactions.

As to the amount of catalyst, in general it has been found that decreasing the amount of catalyst below 0.15 mole per mole of crotonic ester results in material increases in yields. Thus at catalyst mole ratios of about 0.15 per mole of crotonic ester yields of approximately 67% are obtained. At a catalyst mole ratio of approximately 0.1, a yield of about 74% is obtained. At catalyst mole ratios below 0.1 yields within the range of about 82% to about 89% are obtainable. At a mole ratio of approximately 0.15, there seems to be a marked change in the yield of dicrotonic ester obtained, and the yields improve as further reductions in the mole ratio of catalyst are employed. The invention, therefore, contemplates the employment of catalyst mole ratios not in excess of 0.15 and preferably within the range of 0.01 to 0.1.

Example 1

One hundred and fifty grams of dry benzene and 150 g. of ethyl crotonate were placed in a flask fitted with a mechanical stirrer and condenser protected by a calcium chloride tube. Then 1 g. sodium freshly cut in small pieces was added. The mixture was stirred and refluxed for nine hours. By this time it had become deep brown in color and the pronounced odor of ethyl crotonate had disappeared. It was cooled and shaken with dilute sulfuric acid and then washed with water and dried. The benzene was distilled off and the ester product distilled in vacuum. 129.9 grams of product boiling 137-9° C./17 mm. was obtained. A portion of this ester was hydrolyzed to the dicrotonic acid, which melted at 128-9° C. Its neutral equivalent was 86.

Example 2

500 grams of dry xylene (commercial xylol) and 500 g. of ethyl crotonate were refluxed and stirred with 5 g. of fresh sodium methoxide for six hours. During this time the reaction was protected from the moisture of the air by a calcium chloride tube. The mixture was cooled and stirred well with dilute acetic acid, then washed and worked up as in the previous case. The yield was 443 g. of dicrotonic ester product, boiling at 145-150° C./20 mm. Some of the ester was hydrolyzed to give the same dicrotonic acid as before.

Example 3

50 grams of methyl crotonate and 50 g. of a petroleum ether marketed commercially under the name, Skellysolve-C, were refluxed with 1 g. of metallic sodium for eight hours with stirring and with the usual precautions against moisture. After the reaction product had been worked up, ten grams of unchanged methyl crotonate was recovered and 34 g. of the dicrotonic ester was produced. Boiling point 130-4° C./16 mm.

Example 4

50 grams of ethyl crotonate and 50 g. of dry toluene were refluxed with 1 g. of sodium ethylate in the manner described above, for five hours. The product was acidified and washed in the usual manner. Forty-one and seven-tenths grams

of dicrotonic ester product boiling at 139-144° C./18 mm. was obtained.

Example 5

Seventy-five grams of butyl crotonate and 75 g. of xylene were refluxed with 1 g. of metallic sodium for eight hours. The mixture was cooled and stirred with dilute sulfuric acid. After washing and drying, the solvent was distilled off and the ester product distilled in vacuum. Sixty-five and eight-tenths grams of distillate boiling at 146-154° C. at 18 mm. was obtained. There appeared to be no unchanged butyl crotonate.

Example 6

Fifty grams of dibutyl ether and 50 g. of methyl crotonate were refluxed for eight hours with metallic sodium as catalyst. The reaction product was treated in the usual manner as described previously. Thirty-six grams of the dicrotonic methyl ester, boiling at 120-4° C./16 mm. was produced.

Example 7

Fifty grams of ethyl crotonate and 50 g. of xylene were refluxed with 1 g. of metallic potassium freshly cut in small pieces. The reaction mixture was mechanically stirred and protected from moisture by a calcium chloride tube. After seven hours the mixture was cooled and worked up as in the previously described examples. There was obtained 41 g. of the dicrotonic ester product which was found to boil at 145-150° C./20 mm.

Example 8

One hundred grams of methyl crotonate and 100 g. of benzene were refluxed with 5.4 g. of powdered sodium methoxide for a period of eight hours. The reaction mixture was mechanically stirred and protected from moisture in the air by means of a condenser fitted with Drierite tube. Then the mixture was cooled to room temperature and shaken with 4% acetic acid and finally washed with water and dried over anhydrous sodium sulfate. The benzene was distilled off and then the ester product was separated by fractional distillation. There was recovered 6.1 g. of methyl crotonate and there was obtained 69.2 g. of methyl dicrotonate. A dark residue weighing 8.8 g. was left after distillation. The methyl dicrotonate had a boiling point of 128-134° C./24 mm. The n_D^{25} was 1.4508.

Example 9

One hundred grams of methyl crotonate and 100 g. of benzene were refluxed with 8.1 g. of powdered sodium methoxide for a period of eight hours. The reaction mixture was mechanically stirred and protected from moisture by means of a condenser fitted with a Drierite tube. Then the reaction mixture was cooled to room temperature and shaken with dilute acetic acid and finally washed with water and dried over sodium sulfate. The benzene was distilled off and then the ester product was separated by fractional distillation. There was recovered 3.1 g. of low-boiling distillate consisting mainly of methyl crotonate and there was obtained 65.8 g. of methyl dicrotonate. A dark residue weighing 9.8 g. was left after the distillation. The methyl dicrotonate

boiled at 128-133° C./24 mm. The n_D^{25} was 1.4509.

I claim as my invention:

1. Process of condensing a crotonic ester to a dicrotonic ester, which comprises subjecting the crotonic ester in the liquid phase to a temperature within the approximate range of 70-200° C. in the presence of a condensation catalyst selected from the group consisting of alkali metals and alkali metal alkoxides in a mole ratio below 0.15 based on the crotonic ester.
2. Process of condensing a crotonic ester to a dicrotonic ester, which comprises subjecting the crotonic ester dissolved in a high boiling solvent which is relatively inert to the reactants, in the liquid phase to a temperature within the approximate range of 70-200° C. in the presence of a condensation catalyst selected from the group consisting of alkali metals and alkali metal alkoxides in a mole ratio below 0.15 based on the crotonic ester.
3. Process of condensing a low aliphatic crotonic ester to a dicrotonic ester, which comprises subjecting the low aliphatic crotonic ester in the liquid phase to a temperature within the approximate range of 70-200° C. in the presence of a condensation catalyst selected from the group consisting of alkali metals and alkali metal alkoxides in a mole ratio below 0.15 based on the low aliphatic crotonic ester.
4. Process of condensing a crotonic ester to a dicrotonic ester, which comprises subjecting the crotonic ester in the liquid phase to a temperature within the approximate range of 70-200° C. in the presence of a condensation catalyst selected from the group consisting of alkali metals and alkali metal alkoxides in a mole ratio not substantially in excess of 0.1 based on the crotonic ester.
5. Process of condensing a crotonic ester to a dicrotonic ester, which comprises subjecting the crotonic ester in the liquid phase to a temperature within the approximate range of 70-200° C. in the presence of an alkali metal condensation catalyst in a mole ratio below 0.15 based on the crotonic ester.
6. Process of condensing a crotonic ester to a dicrotonic ester, which comprises subjecting the crotonic ester in the liquid phase to a temperature within the approximate range of 70-200° C. in the presence of an alkali metal alkoxide condensation catalyst in a mole ratio below 0.15 based on the crotonic ester.
7. Process of condensing a low aliphatic crotonic ester to a dicrotonic ester, which comprises subjecting the low aliphatic crotonic ester in the liquid phase, while dissolved in a high boiling aromatic hydrocarbon solvent which is inert to the reactants, to a temperature within the approximate range of 70-200° C. in the presence of not substantially in excess of 0.1 mole of a condensation catalyst selected from the group consisting of alkali metals and alkali metal alkoxides, based on the low aliphatic crotonic ester.
